UNITED STATES PATENT OFFICE.

THOMAS GROSERT AND ERNEST UNGER, OF NEW YORK, N. Y.

HAIR-STEAMING DEVICE.

1,029,361.

Specification of Letters Patent. Patented June 11, 1912.

Application filed November 16, 1911. Serial No. 660,592.

To all whom it may concern:

Be it known that we, THOMAS GROSERT, a resident of the city of New York, borough of Manhattan, in the county and State of New York, and ERNEST UNGER, a resident of the city of New York, borough of the Bronx, in the county and State of New York, both citizens of the United States, have invented a new and Improved Hair-Steaming Device, of which the following is a full, clear, and exact description.

Our invention relates to a hair steaming device, and an object of the invention is to provide a heated tube adapted to surround the coil of wet hair, to steam the same.

With the above and other objects in view, as will more fully appear, the present invention consists in certain novel details of construction and arrangement of parts herein-20 after described.

We attain the above outlined objects by disposing a coil of hair within one of a pair of concentric tubes, between which tubes is disposed a resistance to electric energy, by means of which the tubes are heated. Suitable heat-insulating material surrounds the working parts, and means are afforded for suspending the device in any suitable position.

Reference is to be had to the accompanying drawings, forming a part of this specification, in which similar characters of reference indicate corresponding parts in all the figures, and in which—

Figure 1 is a side elevation showing a preferred embodiment of our invention; Fig. 2 is a horizontal transverse sectional view taken on the plane indicated by the line 2—2 of Fig. 1 and looking in the direction of the arrow; Fig. 3 is a perspective view showing the outer insulation removed and the inner tube partly removed from the outer tube, and Fig. 4 is a rear elevation showing the bore-closing door.

Described more in detail, our invention comprises an inner tube 5, relatively long compared to its diameter, one end of which tube is flared outward to form a curl 6, the other or rear end of which tube is externally screw-threaded, as shown at 7. Engaging the threaded end 7 is a spacing ring 8, having an aperture 9 extending longitudinally therethrough, which ring is spaced some distance from the adjacent end of the inner tube 5. Engaging the threads 7, adjacent the end, is a plate 10, having a pair of

diametrically - disposed apertures, through which extends a wire forming a foundation for a handle 11, the ends of which wire are engaged by a pair of nuts 12, one on each side of the plate 10 and bearing upon said plate, to rigidly hold said wire in position. The wire is substantially U-shaped, the outer end 13 being bent upwardly, as shown in Fig. 1, to bring the same out of alinement with the bore of the inner tube 5, so that ready access may be afforded to said bore from the inner end of the device. The bore is normally closed by means of a hinged plate 14 (see Fig. 4), which plate contains an aperture 15, affording means for the escape of the steam through said plate.

Disposed about the outer end of the inner tube 5, is a ring spaced member 16 of some insulating material, the forward edge of which forms a rounded continuation of the curl 6. Disposed about the inner tube 5 and spaced substantially equi - distant between the rings 8 and 16, is an insulating spacing ring 17, and disposed between the insulating rings 16 and 17 is some suitable form of high electric resistance material 18, the passage of electric current through which by means of the insulated leads 19, heats the material 18, as is common with electric heaters. The leads 19 pass through the ring 17, through the aperture 9 in the ring 8, to any suitable source of electric power.

Encircling the inner tube 5 and spaced therefrom, by means of the rings 8, 17 and 16, is an outer metal tube 20, one end of which is curled outward, to form a flange 21 disposed adjacent the ring 16, the opposite end of which has a pair of diametrically - disposed recesses 22 adapted to telescope the nuts 12, so as to bring the inner edge 23 flush with the plate 10.

In order to hold the outer tube 20 in place, as well as to afford a holding means by which the device may be suspended, an aperture 24 is formed in the top of the outer tube 20, which aperture is adapted to be brought into alinement with a threaded recess 25 in the top of the ring 8, through which aperture is extended the threaded end 26 of a U bail 27, the opposite end of which bail has a notch 28 therein, adapted to be sprung into a recess 29 in the top of the outer tube 20. Adjustably mounted upon the bail 27, is a suspending hook 30, held in place by a jam nut 31. By means of this

hook, the device may be suspended from any suitable support and at any desired angle.

To permit the ready handling of the device when heated, a heat insulating material 32 is wrapped about the outer tube 20 and extends from the flange 21 to the plate 10.

Having thus described our invention, we claim as new and desire to secure by Letters 10 Patent:

1. In a means for steaming hair, an inner tube, an outer tube spaced therefrom, a heating means disposed between said tubes and at one end thereof, an insulating handle extending from said tubes, and means for suspending said device in adjusted position.

2. In a device for steaming hair, a pair of concentrically-disposed and telescoped tubes, means maintaining said tubes spaced from each other, electric resistance disposed between said tubes, and a removable plate normally closing the bore of the inner of said tubes, said closing plate having an aperture therein, to permit the escape of steam from the end of the bore of said inner tube.

3. In a hair-steaming device, a tube having one end thereof flared outward and the opposite end externally screw-threaded, a spacing ring engaging said screw-threaded end, adjacent the end of the tube, a plate in screw-threaded engagement with said tube at the end, a handle connected to said end plate, an outer tube collapsing said inner tube and held spaced from the same by said ring, said outer tube abutting said plate, and electrical heating means disposed between said tubes.

4. In a hair-steaming device, an inner

tube, a spacing ring carried by said tube, an outer tube spaced from said inner tube by 40 said ring, a heating means adapted to be disposed between said tubes, a U-shaped bail having one end thereof passing through said outer tube and engaging said ring, and means for removably connecting the other 45 end of said bail with said outer tube.

5. In a hair-steaming device, an inner tube, a spacing ring carried by said tube, an outer tube spaced from said inner tube by 50 said ring, heating means disposed between said tubes, a U-shaped bail having one end thereof passing through said outer tube and engaging said ring, means for removably connecting the other end of said bail with said outer tube, a movable hook carried by 55 said bail, and means carried by said hook for locking the same on said bail.

6. In a hair-steaming device, an inner tube adapted to contain the hair, an outer tube encircling and spaced from said inner tube, electrically energized heating material disposed between said tubes and at one end thereof, a handle extending from said device at the end opposite the end containing the heating material, and electric leads for said 60 material entering said outer tube at the end having the handle.

In testimony whereof we have signed our names to this specification in the presence of two subscribing witnesses.

THOMAS GROSERT.
ERNEST UNGER.
